M. RIMLAND

SPRING STRUCTURE

Filed April 9, 1925

UNITED STATES PATENT OFFICE.

MORRIS RIMLAND, OF NEW YORK, N. Y.

SPRING STRUCTURE.

Application filed April 9, 1925. Serial No. 21,862.

To all whom it may concern:

Be it known that I, MORRIS RIMLAND, a citizen of the Republic of Poland, residing at New York, in the county of Bronx and State of New York, have invented certain new and useful Improvements in Spring Structures, of which the following is a full, clear, and exact specification.

This invention relates to improvements in spring structures adapted for use in connection with cushion seats, for chairs, vehicles, or the like.

The primary object of the invention is the provision of an improved structure wherein the spring supporting means may be practically stitched and assembled in its entirety before the final insertion of the spring members.

Another important object is to provide means whereby each spring member is enclosed in an individual cell of fabric material for the purpose of preventing overlapping and clashing of said springs due to displacement from their vertical positions.

Still further objects reside in the novel and improved features of construction, arrangement and combination of parts herein-after fully described and succinctly defined, the preferred embodiment of the invention being depicted in the accompanying drawings, wherein—

Figure 1 is a plan view of my spring structure, a portion thereof being broken away to illustrate the cellular construction thereof and certain stitching.

Fig. 2 is a vertical longitudinal section taken substantially on the plane of the line 2—2 of Fig. 1, certain of the spring members being removed.

Fig. 3 is a central transverse section taken on the line 3—3 of Fig. 1; and

Fig. 4 is a plan view illustrating how a piece of fabric may be cut to form the base, side walls and a portion of the top of my structure.

Referring now more in detail to the accompanying drawings, wherein like characters of reference denote similar parts throughout the several views, it will be noted that my improved spring structure comprises essentially a casing, denoted gen-

erally by the numeral 5, containing a plurality of coiled springs 6, said springs being inclosed in individual cells 7, defined by 55 longitudinal and transverse partitions, 16, 22, 17 and 26. By this cellular construction, I believe a spring cushion is developed far superior to prior devices, in that the springs are held in proper spaced relation by said partitions, thereby preventing overlapping and rubbing thereof when depressed.

My spring structure will be better understood by a detailed description of the manner in which it is made.

Each casing is preferably of cloth fabric, such as burlap, duck, canvas or the like, and is cut in the form of the blank shown in Fig. 4, the dimensions thereof depending of 70 course upon the number of springs to be used and the particular dimensions of the springs themselves.

The numeral 8 denotes the base of my structure and is bounded by the dotted lines 75 8^a, Fig. 4, while the flaps 9, 10, 11 and 12 are the ends or side walls. The sections marked 13 and 14, of said flaps 11 and 12, comprise a portion of the top of said casing, as will be hereinafter pointed out.

A row of springs having been placed on the base 8, as indicated by the dot and dash circles, the flap 12 is then brought up and over the top of said springs and the edge of the section 14 inturned under the top terminal convolution of said springs, as indicated at 15, Fig. 3. Another row of springs may be placed adjacent the flap 11, and similarly the latter is brought up and in-turned under the springs. Two more rows 90 of springs having been provided, two pieces of fabric 16 and 17 are secured to the base 8, adjacent the lower convolution of said springs, as indicated at 18 and 19, and are brought up and over said springs, then in-turned, as indicated at 21. Each of these pieces of fabric extend longitudinally of the casing and adjacent their abutting ends is vertically positioned a third piece of fabric 22, the lower edge thereof being secured 100 to the base 8, as indicated at 23, while its upper edge may be secured to said abutting ends.

The flaps 9 and 10 may now be brought

up, their upper edges turned outwardly and secured to the overhanging top of the casing, as indicated at 24, Figs. 1 and 2. The opposite ends of said flaps are inturned and 5 stitched to the ends of the flaps 11 and 12, as best shown at 25, Fig. 1.

On inspection of Figs. 1 and 3, it will be observed that I have now constructed a casing provided with longitudinal partitions 10 and it remains only the provision of transverse partitions to form the cells hereinbefore referred to.

To this end short sections of fabric 26 are secured to the base 8 and the top of said 15 casing, their vertical edges abutting the longitudinal partitions 16, 17 and 22. This construction will be clearly understood on reference to Figs. 1 and 2, wherein 27 and 28 denote the points where said sections 26 20 are stitched or otherwise secured. Attention is directed to the fact that said sections 26 have their free ends adjacent the longitudinal partitions.

In order to conceal the meeting points of 25 the inturned ends of the sections forming the top of said casing, I provide narrow strips of fabric 29, having their extremities secured to the casing and being further provided with longitudinal central stitching 30, 30 which in each case embraces the top convolution of said springs and also the meeting or abutting edges of the top sections, as best shown at 31, Fig. 3. This stitching provides additional means for steady 35 said springs, and I also prefer to stitch a portion of said springs to the base as indicated at 30^a, Fig. 3.

It is manifest that in the event I desire 40 to construct the casing before the final insertion of the springs, it is only necessary to dimension the flaps 11 and 12 according to the height and diameter of the springs to be used. In this instance the dotted lines 32 and 33 indicate the top of the longitudinal 45 walls, or perhaps preferably called side walls. The lower edges of sections 16, 17 and 22 are secured to the base 8 and their upper edges left free. The flaps 9 and 10 are now brought up and stitched as previously 50 described, while one edge of the narrow strips 29 may be stitched to the top of the casing. The essential parts of the casing are now in assembled position, and since the sections 26 are only secured to the base and 55 top of said casing, it is only necessary to break open the same adjacent the abutting edges of the partitions 16, 17 and 22, and insert the springs. The stitching 30 and 30^a is applied thus completing the structure.

60 It is obvious that various modifications may be made in the construction shown in the drawings and above particularly described, all within the principle and scope of my invention.

65 I claim:

1. A device of the character described consisting of a coiled spring-contained cellular casing, said casing comprising a single piece of fabric folded to form the base and side walls, and extending over a portion of the 70 top of said casing, a plurality of fabric partitions rising vertically within said casing and having their upper edges folded and inturned to complete the top thereof and a series of transverse partitions secured to 75 the top and base of said casing and presenting free edges adjacent its longitudinal side walls and partitions.

2. A device of the character described consisting of a coiled spring-contained cellular 80 casing, said casing comprising a single piece of fabric folded to form its base and side walls and having a portion extending over its top, vertical partitions within said casing rising between rows of springs, said partitions being secured to the base of said casing and having their upper portions folded in a manner that their ends abut and complete the top of said casing, and a central 85 partition secured to the base of said casing and rising vertically therein between rows of springs and having its free end adjacent the abutting ends of the first-named partitions.

90 3. A device of the character described consisting of a coiled spring-contained cellular casing, said casing comprising a single piece of fabric folded to form its base and side walls and having a portion extending over its top, vertical partitions longitudinally arranged within said casing and rising between rows of springs, said partitions being secured to the base of said casing and having their upper portions folded in a manner that their ends abut and complete the top of said 95 casing, a central partition secured to the base of said casing and rising vertically therein between rows of springs and having its free end adjacent the abutting ends of the first-named partitions, a series of transverse partitions secured to the top and base of said 100 casing and presenting free edges adjacent its longitudinal side walls and partitions, a plurality of longitudinal strips lying over the extremities of said single strip of fabric and over the abutting ends of the first-named vertical partitions, and means for securing said strips to the casing, said means comprising stitching which embraces the top terminal convolutions of said springs and the 110 abutting ends of the vertical partitions.

115 4. A device of the character described embodying a coiled spring-contained cellular casing, said casing comprising a single piece of fabric folded to form its base and side walls and having a portion extending over its top, the inner edges thereof being inturned under the top convolutions of an adjacent row of springs thereby preventing 120 lateral displacement of the latter, vertical 125

partitions within said casing rising between rows of springs, said partitions being secured to the base of said casing and having their upper portions folded over said springs to complete the top thereof and having their inner abutting ends inturned under the top convolutions of an adjacent row of springs, and a central partition secured to the base of

5

said casing, rising vertically therein between rows of springs and having its free end adjacent the abutting inturned ends of the first-named partitions.

In testimony whereof I have signed my name to this specification.

MORRIS RIMLAND.
